UNITED STATES PATENT OFFICE

2,651,419

VIBRATING SCREEN

George Overstrom, Alhambra, Conrad Overstrom,
Altadena, and Gustave A. Overstrom, Alhambra, Calif.

Application June 30, 1950, Serial No. 171,458

15 Claims. (Cl. 210—196)

1

This invention relates to improvements in vibrating or oscillating screens or analogous apparatus particularly suited to the screening of physical mixtures of liquids and finely divided solids, as for example vegetable oils of the edible variety such as palm oil, corn oil, olive oil and peanut oil.

An important object of this invention is to provide a novel combination of elements forming a screening apparatus in which the elements are so related that there is imparted to the screen cloth forming part of the combination a motion which will agglomerate the finely divided solid content of a liquid feed and continuously cause this agglomerate to travel to the reject end of the screen cloth without interruption in its forward travel and at the same time drive the liquid portion of the mixture substantially free of solid content through the screen cloth.

Another important object of this invention is to provide a combination of this nature in which the motion of the screen cloth is such as to agglomerate the fragile solid content of a liquid and convey this solid content the length of the screen cloth without disintegrating it, even though it may be relatively easily disintegrated.

Another object of this invention is to provide a screen combination in which the component parts are so arranged as to produce a motion in the screen box and the screen cloth mounted therein that tends to drive the liquid ingredient of a feed of a mixture of liquid and solid material through a fine mesh screen cloth and at the same time agglomerate the solid content of the mixture so that it will not pass through the meshes of the cloth even though fine enough to do so in its original state.

Another object of this invention is to provide a vibrating screen combination for screening liquids with a solid content by a motion of the screen cloth which will agglomerate the solid content suspended in the liquid and cause this agglomerate to pass off the end of the screen cloth even though the openings in the cloth are larger than the particle size of the solid content of the mixture passing over the screen cloth.

Another object of this invention is to provide a vibrating screen combination including a screen cloth which imparts a motion to the cloth such as will drive the liquid component of a mixture of liquid and solids through the fine mesh of the screen cloth while at the same time rejecting the undersized solid content of the mixture.

Another object of this invention is the provision of a novel method of imparting motion to a

2

screen cloth so that a liquid feed having finely divided solid material suspended therein fed to the screen cloth will have imparted to the liquid a motion which will cause the liquid to be driven through the screen cloth and its solid content to agglomerate and travel to the reject end of the screen cloth without interruption in its forward motion along the cloth.

Other objects of this invention will be made apparent from the following description of several forms of screening apparatus combinations in accordance with this invention.

In the accompanying drawings,

Figure 1 is a side elevational view of one form of screening apparatus in accordance with this invention;

Figure 2 is a transverse, cross-sectional view taken on the line 2—2 of Figure 1;

Figure 3 is a cross-sectional detail view taken on the line 3—3 of Figure 1;

Figure 4 is a vertical, central, longitudinal, cross-sectional view through the apparatus of Figure 1;

Figure 5 is a side elevational view somewhat diagrammatic in form illustrating a modified screening apparatus in accordance with this invention;

Figure 6 is a similar view of a still further modification of this invention;

Figure 7 is a similar view of a still further modified form of apparatus in accordance with this invention;

Figure 8 is a detailed cross-sectional view taken on the line 8—8 of Figure 7;

Figure 9 is a side elevational view of another modification of this invention showing the screen box supported from above;

Figure 10 is a diagrammatic side elevational view of the screen box of any one of the forms of apparatus herein disclosed showing the positions along the screen at which cards of motion were taken;

Figure 11 is a diagram of the motions of the screen box and screen cloth contained therein at the points along the screen box as indicated in Figure 10; and

Figure 12 is a diagram of motion of an orthodox screening machine showing the motion of the screen box and the cloth contained therein at the feed and discharge ends, such as is produced in vibrating screens of the type illustrated in United States Patent No. 1,621,949 granted March 22, 1927, to Gustave A. Overstrom, and United States Patent No. 1,995,435, granted March 26, 1935, to Gustave A. Overstrom.

From experience it has been found that the operation of previously known vibrating screens of the type disclosed in the two above mentioned patents is not effective to successfully screen a liquid containing a fragile finely divided material such as for example hot palm oil. It was found that the fuzzy brown solid content of such oil is disintegrated by screening apparatus of the type disclosed in said patents and caused to pass through the screen cloth along with the liquid after a short travel along the screen path so that a separation of this solid content from the liquid carrier could not be effected.

The screening machines of this invention are so constructed that the motion of the screen cloth is such as not to permit the solid content of hot palm oil, for example, to pause in its travel along the screen cloth, with the result that it quickly agglomerates without disintegration and is discharged over the end of the cloth while the liquid component is driven through the cloth substantially free of solid content.

Prior to this invention it has not been possible to free palm oil of its undesirable solid content by means of screens of the vibrating type. Edible oils are generally expelled through such machines as Anderson or French expellers, although in some cases solvent extraction and high pressure steam extraction have been used. None of these methods are completely satisfactory for many reasons well understood in the art. For example, when edible oils of this type are expelled there is a dry meal discharged from one end of the expeller and an oil bearing an undesirable quantity of meal discharged from the other end of the expeller. In an effort to remove this meal from the oil it is placed in settling tanks and the supernatant liquid is drawn off but, as is well known, this liquid still contains minute particles which in the case of palm oil are "phosphatides." As is well understood phosphatides are tri-hydric and one OH component generally goes with any glycerine present, and another goes to form a fatty or oleic acid. As a result these components are easily subject to oxidation resulting in decomposition which is the source of an undesirable stench. Prior to this invention no effective method or apparatus has been developed to sufficiently eliminate these difficulties with the result that it has been common to ship edible oils such as palm oil under refrigeration.

If the solid content of such oils which average 10 microns in size can be removed or substantially so, such oxidation is slowed down and further processing simplified.

Since the solid content of such oils is as fine as 10 microns in size the vibrating screening machines of this invention employ fine mesh screen cloths of a mesh, for example, of 120 and finer. In some cases screens of 200 square mesh have been used. As disclosed herein when such fine screen cloths are vibrated through paths of motion such as will be hereinafter disclosed, these fine particles are caused to agglomerate and travel continuously along the screen cloth to the reject end. The liquid component of such oils for example that passes through the screen cloth is further processed in a centrifuge. It is common practice to centrifuge the oil after as much of the solid content as possible has been removed therefrom. The oil recovered by prior processing has contained sufficient solid content to cause the centrifuge to plug at its jets. Without the use of the screening machines of this invention

the centrifuge had to be shut down after a short run and the bowl cleaned. Centrifuging the liquid component recovered from the screens of this invention has been simplified by reason of the fact that the running time of the centrifuge without cleaning has been increased from a fraction of an hour to a total time between bowl cleanings, as shown by the following table:

100 x 100 mesh	120 x 120 mesh	150 x 150 mesh	200 x 200 mesh
1/4 hour	3 hours	8 hours	41 hours

The result is that a considerable saving in labor time is effected and since the running time of the centrifuge is greatly increased a much improved overall efficiency of the process is effected.

A detailed description of the structure of the components of this invention and their relationship will first be given followed by a discussion of the effects and advantages thereof.

Referring to the drawings the form of apparatus illustrated in Figures 1 to 4 inclusive includes a screen box 1 of any suitable construction. As illustrated it consists of a pair of longitudinal side members connected by suitable cross braces such as the angle irons 23. A pair of brackets 3 are attached to the feed end of the screen box 1 at opposite sides and on the bottom thereof, and similarly a pair of brackets 3 are attached to the opposite end of the screen box 1 on opposite sides thereof at the top. Each of these brackets has mounted therein a transversely extending pintle 3' which may be mounted on their respective brackets in any suitable manner. Mounted on the pintles 3' at the centers are the involutely coiled springs 4 having tangential tails which are firmly attached by means of suitable clamps 4' to the base frame 2. The base frame may be built up in any suitable and well known manner to provide a support for the screen box through the springs 4. Mounted on the side frames of the screen box 1 toward the discharge end of the screen box are a pair of brackets 5 which are constructed to provide a mounting for the driving member 6 which imparts vibration to the screen box. This driving member in principle consists of a rotating unbalanced weight which may be provided in various forms, a very suitable one of which is disclosed in United States Patent No. 2,304,198 granted December 8, 1942, to Gustave A. Overstrom et al. This driving mechanism for imparting vibration to the screen box as shown in detail in that patent is entirely suitable for use in the various screening combinations herein disclosed.

On the end of the unbalanced shaft forming part of the driving mechanism 6, is mounted a pulley 7 connected by a belt 8 to a drive pulley mounted on the shaft of the driving motor 9, which motor in turn is supported by a suitable cradle 9', attached to the side of the base frame 2, as shown in Figure 1.

At the feed end of the screen box 1 is a framework 10 of any suitable construction comprising vertical and cross members firmly secured to the base frame 2 and supporting a liquid distributor box 11 having a feed pipe connection 12. Within the box 11, as shown in Figure 4, is a baffle wall 11' onto which the liquid is discharged from the pipe 12 and from there distributed in a sheet transversely of the screen box onto the bottom wall of the box 11, from which it flows

onto the screen cloth 13. This screen cloth is mounted in the screen box 1 so as to be stretched to the proper tautness both longitudinally and transversely.

The screen cloth is mounted in the box and properly stretched by means of the following mechanism. The cloth itself is provided at each end with a reinforcing strip 14 of hook shaped formation in cross section, as clearly shown in Figure 4. Likewise attached to the longitudinal side edges of the screen cloth are reinforcing strips 14^a of hook shaped formation in cross section, as clearly shown in Figure 3. Extending longitudinally of the side members of the box 1 are a pair of angle irons 1' (see Fig. 3) attached to the box side members in any suitable manner, as by welding in the case of metal. The screen cloth 13 extends transversely of the box and rests at its reinforced side edges on the angle supports 1'. The screen cloth is stretched transversely by means of U-shaped channel members 15 extending longitudinally of the screen cloth and fulcrumed on their upper edges on the box side members 1, as clearly shown in Figure 3. The opposite longitudinal edge of the channel members 15 engages in the hook shaped reinforced edge 14^a of the screen cloth throughout its length. Bolts 17 pass through a strip 15' extending along the outer faces of the channel members 15, properly positioned by means of dowel pins 15'' mounted in the members 15. The bolts, of which there are several, as indicated in Figure 4, are engaged by means of nuts 16 bearing on suitable formations in the box side members 1 so that as the nuts are tightened the channel members 15 fulcrum in a direction to stretch the screen cloths 13 transversely. A series of U-shaped springs 40 lie between the channel members 15 and the frame members 1, so that the terminal ends of each spring engages in socket 41 secured to the member 1, and the closed end bears against the inner face of the channel member 15 and passes under pin 15''. These springs aid in the outward fulcrum movement of channels 15 as the nuts 16 are eased off, and the member 15 is supported by the pins 15'' resting on them.

The screen cloth 13 is stretched longitudinally in the following manner. An angle iron 18 extends transversely of the box side members 1 and is permanently secured between them in a position so that the hook reinforcing strip 14 at the feed end of the screen cloth is engaged thereover, as shown in Figure 4. On similar principles channel member 18' is secured adjacent the discharge end of the screen. The reinforcing hook shaped strip 14 at this end of the screen cloth engages in hooks or projections on a tubular member 19 which rests on the channel 18' and is rotatable on its axis. A series of clamping devices comprising nuts and bolts 20 and clamping blocks engaging the tube 19 are provided to clamp this tube in various rotated positions on the fixed angle iron 18'. Thus with reference to Figure 4, it will be seen that by rotating the tube 19 the screen cloth 13 can be stretched longitudinally against the resistance of its anchored opposite end. When stretched to the proper degree longitudinally the tube 19 is clamped by means of the nuts and bolts 20. As indicated in Figure 4, the bolts 20 pass through diametrically aligned slots in the tube 19 of sufficient length to permit of sufficient rotational movement of the tube 19 to insure proper tensioning.

There is shown in Figure 3 one of several lon-

gitudinally extending substantially I-shaped beam members 22 which are mounted upon the transverse reinforcing members 23 of the screen box. The longitudinal top edge of each of the members 22 is covered with a resilient covering such as soft neoprene rubber to minimize the wear of the screen 13 at the point of engagement with these supports for the screen cloth.

Supported under the screen box and in the base frame 20 is a stationary collecting and drain pan 24 having a discharge connection 25 through which the liquid which passes through the screen can be withdrawn. A drip strip 24' insures that liquids are directed into the drain pan 24.

Several of the more important structural features and relationship of component elements of this structure are best emphasized at this point. From the above description it will be seen that the frame forming the screen box and in which the screen cloth 13 is mounted for vibration therewith, is supported at each corner by means of involutely coiled springs which in turn are fixed upon the base frame 2. It will be noted that the driving means 6 which imparts vibration to the screen box is mounted towards the lower end of the inclined screen box and in the case of the structure so far described and adjacent to the supporting springs for the lower end of the box. It will also be noted that the screen cloth 13 terminates at its high end at a point somewhat spaced from the supporting springs for the high end of the screen box and terminates at its other end at a point spaced inside of not only the supporting springs 4 for the lower end of the box but of the driving mechanism 6. Thus the driving member 6 is mounted relatively close to the supporting springs at the lower end of the box and near to or beyond the reject or discharge end of the screen cloth. These are very important relationships of elements in order that there be imparted to the screen cloth itself a motion which will effect the separation of solids from liquids of the type previously described in a highly efficient manner.

As those skilled in this art will appreciate or can learn by simple test, there can be some variation in the location of the driving member 6 with respect to the adjacent screen box support while attaining satisfactory results, but it is essential to the type of operation desired by the mechanism herein disclosed that the driving element 6 be mounted on the screen box beyond the reject or discharge end of the screen cloth. This relationship of the driving element to the screen cloth will be found in all the modifications to be hereinafter described. In part at least it is due to this relationship that the finely divided solid content of a liquid will be agglomerated without disintegration and caused to travel continuously to the discharge end of the screen cloth.

In the modification illustrated in Figure 5, the general construction of the parts is similar to that previously described. A box base frame 2 of any suitable construction is provided on which is mounted the screen box 1. In this case the lower end of the inclined screen box is supported by involutely coiled springs 4 at opposite sides on the base frame while the higher end of the box in this case is supported by means of flexible resilient legs 26 which are fixedly mounted at their upper ends in suitable fixtures 26^a secured to the screen box 1 and at their lower ends in fixtures 26^b mounted on the base frame 2. In this case the driving element 6 which is the same as that previously described, is also mounted on the

screen box 1, but in a somewhat spaced relation to the springs 4. However, it will be noted that the driving element 6 is positioned beyond the reject end of the screen cloth 13 mounted in the box 1, as previously described.

The modification of Figure 6 is in general similar to that previously described including base frame 2, and inclined screen box 1 supported at its lower end by means of the springs 4. The driving element 6 is again mounted in somewhat spaced relation to the springs 4 on the box 1 beyond the reject end of the screen 13. The difference in this construction over those previously described is in the fact that the involutely coiled springs 4 for the high end of the box are mounted on opposite sides as in the case of Figure 1 and are attached to the top edges of the side members of the box 1. In order to accomplish this the base frame 2 is provided with rigid uprights 2' of sufficient height to provide a support for the tails of the involuted springs 4 through the agency of the clamps 4'.

The modification of Figure 7 is similar to that of Figure 1 with two exceptions, the first of which involves some spacing of the driving element 6 from the adjacent resilient supports for the screen box and yet beyond the discharge end of the screen cloth 13, as in all previous cases. The real difference in the construction herein illustrated is in the resilient mountings for the screen box 1. In the arrangement of Figure 1 the resilient supports comprise involutely coiled springs, whereas in the arrangement of Figure 7 they consist of resilient discs 27 of rubber or other suitable material. The supports for these discs in this case have been modified to accommodate this difference in construction and consist of circular housings 50 mounted on the base frame 2 in which the resilient discs 27 are mounted. The screen box is provided with brackets 3 as in the case of Figure 1, and as clearly shown in Figure 8, are provided with transversely extending pintles 3' which lie in central apertures in the discs 27. Thus these resilient discs or bushings 27 serve to support the screen box for freedom to effect the desired motions of the screen box under the driving forces of the vibrator 6 in a manner quite similar to the motions accomplished when using the involutely coiled springs.

As illustrated in Figure 9 the screen box may be supported from overhead. The screen box, as in previous cases, is provided with the driving element 6 mounted beyond the discharge end of the screen 13. The box itself is supported at each corner from the ceiling or any suitable overhead structure 28 by means of helically coiled springs 29 and suitable attaching links at their respective ends. It will be seen that the general arrangement and location of the supporting spring elements, the vibrator element and the screen cloth is the same as that previously described, the difference being that the screen box is provided with a hanging support.

In the operation of all of these screens the movement of the screen cloth under the action of the driving element 6 is substantially the same at the various points indicated in Figure 10. Sufficient of these points have been taken to give those skilled in the art an accurate idea of the actual motion of the screen cloth which has been diagrammatically illustrated for these points in Figure 11.

As is clearly illustrated in the diagram of Figure 11, depicting the motion of the screen box

and cloth at the points 1 to 9 of Figure 10, the component of vertical movement thereof gradually decreases from position 1 to a point midway of positions 3 and 4 (the neutral point), and 5 then gradually increases from that midpoint to the discharge end. This illustration applies especially to all of the forms of screens shown herein, with the exception of that of Figure 5 in which the motion varies in its detail, but is substantially the same in its over-all effects. As 10 illustrated in Figure 11, the screen cloth at the feed end to the left of the neutral point vibrates in a closed elliptical path having a very small vertical component of movement and a larger horizontal component of movement. The major axis of the ellipse is sharply inclined forwardly, forming a small angle with the horizontal. At points nearer and nearer to the neutral point, the vertical component of screen movement becomes smaller while the horizontal movement becomes greater, so that at the neutral point there is no vertical component of movement. 15 From the neutral point towards the discharge end, as illustrated, the vertical component increases and the horizontal component decreases as illustrated by the elliptical paths of motion, the major axis of which being less and less inclined to the horizontal.

At the discharge end of the screen, these paths 20 of motion are more nearly circular so that the horizontal component is the smallest at this point while the vertical component is at a maximum. It will be noted that this motion diagram is related to the horizontal and, since the screen cloth 25 lies in an inclined plane from the feed to the discharge end, it will be seen that the longitudinal axis of motion is always slightly away from the inclined screen surface. With this type of motion, it is possible to effect agglomeration of the 30 solid content of a liquid, of the type hereinbefore referred to, at the feed end where the vertical motion of the screen is quite small. This vertical motion is accompanied by a forward conveying action represented by the horizontal components 35 of movement, so that the forward motion of the agglomerated material becomes progressively greater in a vertical plane while remaining of the same length in a horizontal plane. This action continues until the agglomerate reaches the 40 point at which the unbalanced revolving shaft is mounted on the box when the paths of motion become more nearly circular, as will be seen progressively from point 7 through point 9. It is not necessary that the motion of the screen 45 be greater in a vertical direction than in a horizontal direction at the discharge end of the screen but only that the vertical motion be greater at the discharge end than at the feed end where the motion, as previously explained, is 50 practically horizontal.

The over-all effect of the structure of Figure 5 is the same as that of the other figures for the purposes of this invention. It will be noted, however, in view of the fact that the flexible leg 55 26 is in a vertical plane, that the neutral point of the screen is at this leg. In other words the screen has no vertical motion at this point, only a horizontal component of movement. In other words the chart of motion of Figure 11 applies 60 to the screen of Figure 5, assuming that the neutral point is at the vertical leg 26. With this assumption the motion of the screen progressively to the right corresponds to the motion at the points 4 to 9 inclusive of that figure. Thus this 65 screen is as fully effective for the purposes of

this invention as are the other structures herein illustrated.

It is as a result of the type of motion thus described that the screen accomplishes the proper forward travel of the liquid feed, effects agglomeration of the finely divided material without substantial disintegration in the case of the fragile material, and the transmission of the liquid through the screen into the drain pan 24. In other words this type of motion tends to agglomerate the finely divided material in a liquid, very fast feed in, and then to subject it to a progressive movement along the screen cloth without interruption in travel until it is rejected at the discharge end thereof. By comparison with Figure 12 it will be seen that the type of motion imparted to the screen cloth is distinctly different from that of orthodox vibrating screens such as illustrated in Patent No. 1,621,949 previously referred to.

At the feed end of that screen the screen cloth travels in closed oval paths with the long axes thereof inclined forwardly and at the discharge end in a similar path with the long axes, however, inclined rearwardly and with a progression of inclination of this axis from the former to the latter at intermediate positions. This type of motion is detrimental in the screening of a liquid containing finely divided material where it is required to reject the finely divided material from the liquid. A motion of that type does not allow the material to agglomerate but causes the finely divided material to pass through the screen cloth openings along with the liquid. The constructions of this invention on the other hand cause agglomeration and prevent movement of the finely divided material through the screen cloth even though it be of a size smaller than the screen openings. The particles instead of going through the screen quickly agglomerate into larger masses which travel along the cloth and are discharged at the end thereof without any hesitation in their movement. All of the modifications herein described so act but not all with the same efficiency.

By way of comparison from actual experience the following relative efficiencies have been observed, although all the structures herein disclosed are commercially feasible to attain the objects herein set forth. The screen of Figures 1 to 4 inclusive which was first tried was commercially satisfactory but turned out not to be so efficient as the screen shown in Figure 5 which was the second type of machine to be tried. The machine of Figure 6 which was next tried showed an increase in efficiency over the two previous structures. In addition to this increase in efficiency there was gained a considerable reduction in manufacturing costs. For comparison purposes it was determined that the ratio of efficiency between the machines of Figures 1, 5 and 6 is about as 15 is to 23 is to 30 as far as throughput of oil is concerned. The reduction of impurities contained in the screened material was about in the ratio of 76.6% for the machine of Figure 1; 86% for the machine of Figure 5; and 94.3% for the machine of Figure 6, when processing hot palm oil. More specifically, when using the machine of Figure 6 it was possible to remove 94.3% of all solids in the hot palm oil above 6 microns in size when the oil temperature was approximately 180° F. It should be noted here that the utility of these screens is not limited to the processing of hot liquids containing finely divided solids, reference being

made to hot palm oil because of the greater practical experience with the processing thereof.

From the above description of the various modifications of our invention herein disclosed it will be apparent to those skilled in the art that construction of the elements and the relationship are capable of variation within the limits of novelty herein disclosed, and we do not, therefore, desire to be strictly limited to the specific embodiments herein illustrated, but rather to the scope of the claims granted us.

What is claimed is:

1. A screening machine comprising a support, an inclined screen box, resilient members attached to the screen box adjacent each end thereof and respectively secured to said support, a screen cloth mounted in said screen box between the points of attachment of said resilient members to said screen box and of a length less than the distance between said points, and vibration imparting means mounted on said screen box between the resilient members at the lower end of said box and the adjacent end of said screen cloth.
2. In the combination of claim 1, said resilient members comprising involutely coiled springs.
3. In the combination of claim 1, said resilient members comprising involutely coiled springs, and means for attaching said springs at their inner ends to said screen box and at their outer ends to said support.
4. In the combination of claim 1, said resilient members comprising involutely coiled springs, the springs at the higher end of the screen box being attached to the underside of the screen box and the springs at the lower end of the screen box being attached to the upper side of the screen box.
5. In the combination of claim 1, said resilient members comprising resilient discs.
6. In the combination of claim 1, said resilient members comprising resilient discs, and means for attaching the discs at their peripheries to said support and at their centers to said screen box.
7. In the combination of claim 1, said resilient members attached to the higher end of said screen comprising flexible struts and means for fixedly attaching said struts at their respective ends to said box and support.
8. In the combination of claim 1, said resilient members attached to the higher end of said screen comprising flexible struts and means for fixedly attaching said struts at their respective ends to said box and support, and said resilient members attached to the lower end of said box being involutely coiled springs.
9. In the combination of claim 1, means for delivering a liquid onto the feed end of said screen cloth in a sheet.
10. In the combination of claim 1, a drain pan mounted on said support below said screen cloth.
11. In the combination of claim 1, said vibration imparting means comprising a rotatably mounted unbalanced weight.
12. In the combination of claim 1, said vibration imparting means comprising a rotatable and eccentrically mounted shaft.
13. In the combination of claim 1, said resilient members comprising springs for suspending said screen box from said support.
14. In the combination of claim 1, said resilient members comprising resilient discs, means for mounting said discs on said support, and means

mounted on said screen box and attached in central apertures in said discs.

15. In a screening apparatus of the type described the combination comprising an inclined screen box having a screen cloth of a length shorter than the length of said box mounted therein, means for resiliently supporting said box at each of the corners thereof, and vibration imparting means mounted on said box between the supporting means for the lower end of the box 10 and the discharge end of said screen cloth.
